(57) **CLAIM**

The ornamental design for a vehicle center console, as shown and described.

DESCRIPTION

FIG. 1 is a rear and left side perspective view of a vehicle center console.

FIG. 2 is a front view of the vehicle center console of FIG. 1.

FIG. 3 is a rear view of the vehicle center console of FIG. 1.

FIG. 4 is a right side view of the vehicle center console of FIG. 1.

FIG. 5 is a left side view of the vehicle center console of FIG. 1.

FIG. 6 is a top view of the vehicle center console of FIG. 1; and,

FIG. 7 is a bottom view of the vehicle center console of FIG. 1.

The dashed lines showing the various parts of the vehicle center console are for illustrative purposes only and form no part of the claimed design.

1 Claim, 7 Drawing Sheets
